CLAIM

The ornamental design for a sweeping robot as shown and described.

DESCRIPTION

The file of this patent contains at least one drawing/photograph executed in color. Copies of this patent with color drawings(s)/Photograph(s) will be provided by the United States Patent and Trademark Office upon request and payment of the necessary fee.

1. Sweeping robot
2. sweeping robot
- 1.1 Front view
- 1.2 Back view
- 1.3 Left view
- 1.4 Right view
- 1.5 Top view
- 1.6 Bottom view
- 1.7 First perspective view
- 1.8 Second perspective view
- 2.1 Front view
- 2.2 Back view
- 2.3 Left view
- 2.4 Right view
- 2.5 Top view
- 2.6 Bottom view
- 2.7 First perspective view
- 2.8 Second perspective view

(Continued)

The portions of the design shown in the color red are for the purpose of illustrating portions of the sweeping robot and forms no part of the claimed design.
